METHOD OF FINISHING ROUNDS

George A. Wise, Pittsburgh, Pa., assignor to
 Sutton Engineering Company, a corporation
 of Pennsylvania

Application April 11, 1935, Serial No. 15,776

3 Claims. (Cl. 80—63)

This invention relates to the cold rolling of solid metallic rounds for sizing and truing them within narrow tolerances.

The cold rolling of round stock, to size and true it, is disclosed in Abramson Patent No. 1,601,551, and in my own Patent No. 1,914,587. The first named of these patents discloses a method in which the round stock is repeatedly scrolled, and the scrolling rolled out, being thus 5 by repeated action reduced in cross-sectional area and brought into closer approximation to true round. Both the Abramson patent and German patent to Wirth & Co., No. 79,642 of 1895, which latter patent discloses the rolling of a 10 tube wall to accurate gauge and the tube to true circular section on a mandrel, permit the stock to elongate as it is reduced in cross-sectional area.

In my prior patent the stock is scrolled by rolling in a pair of cross rolls arranged to have 20 with it a relatively narrow bearing area, and the scroll is subsequently rolled out by passing the stock successively through cooperating pairs of cross rolls having with the stock progressively increasing areas of contact. In this process, elongation of the stock is permitted by increased 25 linear speed in the roll passes from the entering end to the leaving end of the roll assembly, the stock being gripped simultaneously by two or more cooperating pairs of cross rolls during its 30 passage through the roll assembly, or aligned group.

It is customary in the drawings of such patents to show the scrolling and rolling down of the stock, as if the stock were plastic when cold, being thus subject to relatively deep scrolling 35 and to ready flow under the influence of smoothing rolls. This is for the purpose of illustrating the effect of the scrolling and smoothing rolls, since the scrolling of steel rounds extends merely 40 to a depth of from one to three thousandths of an inch, and it is a difficult matter to produce surface flow of the metal even with the relief provided by the scrolling.

The object of my invention is to provide a 45 process of so working cold, or approximately cold rounds that maximum facility for flow of the metal at the surface of the stock is obtained; thus securing to an increased extent reduction in the cross section of the stock, while minimizing the tendency to strain the central metal of 50 the rounds which usually is attendant upon the exertion of a high degree of rolling pressure upon cold stock.

By experiment I have proved that if a round 55 be so scrolled as approximately to isolate rela-

tively small areas on the surface of the stock, the metal may in subsequent rolling down, flow in more than one direction in the intervals provided by the scrolling. There is the further advantage that in cross rolling, round stock frequently so adjusts itself in the pass that the contact area of the roll rides along the line of scrolling, rather than on the high region of the stock adjacent the line of scrolling. In itself, the scrolling of a double spiral on the stock does 10 not materially facilitate rolling down, nor does it improve materially the resulting product.

Primarily considered, my cold rolling process consists in oppositely scrolling the stock to produce thereon spirals opposite in sense, which intersect at intervals along the length of the stock, and then rolling down the stock to the necessary 15 tolerance as to size and true circular section. These opposite and intersecting spirals may be either single or double spirals.

In the accompanying drawing, Fig. I is a schematic plan view of instrumentalities for conducting the process of my invention.

Fig. II is an elevation of a length of round stock upon which a single, uni-directional, spiral 25 scrolling has been imposed.

Fig. III is an elevation of the stock after there has been imposed thereon an additional spiral scrolling, opposite in sense, to that first imposed upon the stock.

Fig. IV is an elevation of the stock, illustrating the step of rolling down the stock after it has been completely scrolled.

Fig. V is an elevation of a length of round stock, which has had imposed thereon a double spiral which is uni-directional in sense.

Fig. VI is an elevation of the stock after an additional double spiral scrolling opposite in sense, has been imposed on it.

Fig. VII is an elevation of the stock, illustrating the step of rolling down the stock which has had imposed thereon the two opposite double spiral scrollings.

Fig. VIII is a side elevation of an initial roll pass, illustrating the imposition of a single spiral 45 scrolling on a length of round stock.

Fig. IX is a side elevation of a second roll pass, illustrating the imposition of a second spiral scrolling, opposite in sense, on the stock.

Fig. X is a side elevation of a roll pass, illustrating the rolling down of the stock upon which the intersecting double scrollings have been imposed.

Fig. XI is a side elevation of a roll pass in which the rolls are arranged to impose a double spiral 55

scrolling on the stock, and illustrating the action of the rolls in spiralling the stock.

It should be explained, in connection with the drawing, that the depth of scrolling is greatly exaggerated, both as to the depth and abruptness of the impression, and that the illustrated regularity in the pattern formed by the scrolling is, in practice, of extremely rare occurrence. Further, it should be noted that the marking on the face of the rolls in Figs. VIII to XI is, of the drawing, merely indicative of the width of bearing surface on the rolls, and does not illustrate a ribbed roll surface.

To describe my process, with reference to the drawing exemplary thereof, Fig. I shows a length of round stock A passed through a cooperating pair of scale-cracking cross rolls 1 and 2, and immediately thereafter passed through a pair of cooperating scrolling cross rolls 3 and 4. In order that the stock may be subjected to a straightening flexion during this initial action thereon, an intermediate pressure roll 5 is mounted between the passes 1, 2 and 3, 4. If desired the stock may, as shown, be passed through this set of cross rolls in such manner that the scale-cracking and initial scrolling are effected progressively along the stock as it moves longitudinally through both passes, and is rotated about its axis.

It will be noted that, as shown in Fig. I, the scrolling *a* produced by the initial treatment of the stock is a uni-directional scrolling in the form of a single thread imposed by a single narrow bearing surface of the scrolling roll on the stock. This scrolling pass is illustrated in detail in Fig. VIII of the drawing. As there illustrated, the roll 3 has a relatively wide area 3a which bears upon the stock, and the scrolling is effected by the relatively narrow bearing surface 4a of the roll 4. As will be seen clearly in Figs. II and VIII, the scrolling of the round stock does not, at this stage of the process, produce areas on the surface of the stock which are wholly, or substantially, isolated by the scrolling. The second pass in which the stock A is treated, comprises desirably the single independent pair of cross rolls 6 and 7, which rolls are so arranged as to impose upon the stock a spiral scrolling opposite in sense to that imposed by the initial scrolling rolls 3 and 4. It is to be understood that the stock must be removed from the initial roll assembly, in which scale is cracked and the primary scrolling imposed, before it is acted upon by the secondary scrolling rolls 6 and 7.

Referring to Fig. IX of the drawing, it will be noticed that the roll 7 has with the stock a relatively wide bearing surface 7a, but that the roll 6 has with the stock a relatively narrow bearing surface 6a. Further it will be observed that the rolls 6 and 7 are inclined to a common axis oppositely to the inclination of the rolls 3 and 4, and that they, therefore, impose upon the stock a spiral scrolling *b*, which intersects the spiral scrolling *a*, imposed by the first pair of scrolling rolls.

Referring to Fig. III of the drawing, it will be seen that this reverse scrolling produces substantially isolated areas on the face of the stock, the imposed scrolling giving relief for the flow of metal in all directions during a subsequent step of rolling down the stock. It also will be clear from an inspection of Fig. III that the purpose of scrolling the stock can not be defeated by travel of the stock through pressure rolls in

such manner that the stock tends to ride along the line of the scrolling. This is for the reason that there is, in any position of the round, relief afforded in a direction angular to each scroll line.

The operation of rolling down is illustrated in Fig. I of the drawing as performed by a single pair of pressure rolls 8 and 9, which, as shown in Fig. X of the drawing, have both with the stock the relatively wide bearing surfaces 8a and 9a. Considering Fig. X of the drawing, it is seen how the bearing surfaces of these pressure rolls 8 and 9 overlap the scrolled surface of the stock, pressing down the high areas lying between the intersecting scroll lines.

As a finishing step the stock is passed through a set of cooperating cross rolls comprising the roll pairs 10 and 11, and 13 and 14, together with the cooperating pressure roll 15. This stage of the final working of the stock is a final rolling down step, as well as a straightening and polishing step. It will be noted that the rolls of this final assembly are inclined to each other in the direction, or sense, of inclination shown with relation to the rolls 6 and 7 of the second scrolling pass. The effect throughout the process is, therefore, one of an alternate, opposite rolling of the stock at the successive stations. Following the scale-cracking between rolls 1 and 2, the stock is scrolled in one directional sense by the cooperating pair of rolls 3 and 4, and in the opposite directional sense by the rolls 6 and 7. The stock has the initial rolling down by the pressure rolls 8 and 9, which are inclined to each other in the sense of the rolls 3 and 4; and has a rolling down and polishing between the pairs of rolls 10 and 11, and 13 and 14, which are inclined to each other in each pair in the same sense as the rolls 6 and 7, and in opposite sense to the rolls 8 and 9.

Desirably in the final treatment of the stock, the rolls 10 and 11 are brought to bear with considerable pressure upon the stock, to effect the final rolling down, while the rolls 12 and 13 bear lightly upon the stock, to effect smoothing and polishing. As stated above, the entire assembly comprises roll pairs 10 and 11, and 13 and 14, together with pressure roll 15, so that it exerts a straightening effect upon the stock.

Referring now to Figs. V, VI, VII and XI of the drawing, I have illustrated the imposition of intersecting double spiral scrolling upon the stock, and the rolling down of such double spiral scrolling. In Fig. V, a double spiral scrolling *c* of the stock B is shown, and in Fig. XI a roll arrangement is shown for imposing upon the stock that scrolling. Rolls 16 and 17, shown in Fig. XI, are a pair of cross rolls, each of which has with the stock a narrow bearing surface shown respectively as the bearing surfaces 16a and 17a. This pair of rolls is, for double scrolling of the stock, mounted in tandem with rolls 1 and 2, replacing the pair of cooperating rolls 3 and 4 for imposing the single spiral *a* upon the stock A.

After the stock has been passed through the pair of rolls 16 and 17, it is passed through a second oppositely inclined pair of rolls corresponding in the process to the roll pair 6 and 7. Fig. VI illustrates the effect produced when both rolls of this oppositely inclined pair have with the stock a narrow bearing surface, to impose upon the stock a double spiral scrolling *d* which is opposite in sense to the spiral scrolling *c*. The stock B is then passed through a finishing stand, or set, of rolls inclined to each other in sense opposite that of the initial scrolling rolls 16 and 17 and

the initial pass of smoothing rolls, and inclined to each other in the same sense as the pass of secondary scrolling rolls.

It will be understood that the imposition of intersecting double spirals tends to the production of areas approximating complete isolation on the surface of the stock more closely than is obtained by the imposition of intersecting single spirals. An intermediate effect may be obtained by imposing on the stock a double spiral scrolling to intersect with a single spiral.

I have observed that the opposite scrolling of the stock results in a finished product of better internal structure than that resulting from the spiralling and subsequent smoothing of round stock upon which a merely uni-directional spiral has been imposed. This is clearly for the reason that there is present a lessened tendency to open the central region of the stock. Also there is apparently produced a deep working of the stock, during the rolling down along lines out of parallelism with the longitudinal axis of the stock. The effect is thus that the higher regions between scroll lines are worked down, rather than pulled along, as the stock is elongated and reduced.

It may be noted further that the imposition of intersecting spirals permits a greater reduction in the cross rolling of the stock than can be effected by the imposition of one spiral scrolling followed by a rolling down of the stock. If it is desired to produce stock which is equivalent, as to sizing, accuracy of section, and finish, to that produced by cold drawing, it may be desirable first to follow the procedure here described, and to then subject the stock to the treatment described in my Patent No. 1,914,587, omitting the blasting step described in that patent. It will be understood that in such multiple process, the rolling during treatment as in my earlier patent may be relatively light.

I claim as my invention:

1. The herein described method of cold rolling solid metallic rounds which consists as a succession of separate and individually complete steps in first rolling a spiral groove of appreciable depth in the stock while providing for rotation of the

stock in one definite angular direction, rolling in the stock a second spiral groove opposite in sense and of appreciable depth intersecting the first groove while providing for rotation of the stock in the opposite angular direction, and restoring an uninterrupted surface to the stock with improvement in approximation to mathematical roundness of the stock by rolling out the intersecting spiral grooves while providing for rotation of the stock.

2. The herein described method of cold rolling solid metallic rounds which consists in approximately isolating areas on the surface of the stock by a succession of separate and individually complete steps comprising rolling in the stock a groove of appreciable depth describing a double spiral about the stock while providing for rotation of the stock in one definite angular direction, rolling in the stock a second spiral groove opposite in sense and of appreciable depth intersecting the first groove while providing for rotation of the stock in the opposite angular direction, and as a separate and individually complete step restoring an uninterrupted surface to the stock with improvement in approximation to mathematical roundness of the stock by rolling out the intersecting spiral grooves while providing for rotation of the stock.

3. The herein described method of cold rolling solid metallic rounds which consists in isolating areas on the surface of the stock by a succession of separate and individually complete steps comprising rolling in the stock a groove of appreciable depth describing a double spiral about the stock while providing for rotation of the stock in one definite angular direction, rolling in the stock a similar double spiral groove intersecting the first groove while providing for rotation of the stock in the opposite angular direction, and as a separate and individually complete step restoring an uninterrupted surface to the stock with improvement in approximation to mathematical roundness of the stock by rolling the stock to cause flow of the metal of said isolated surface areas while providing for rotation of the stock.

GEORGE A. WISE.
